Garrison Smith Henry Brown & Julius Bolzer of Philadelphia Pa
assignors to

North Harrison & Chase of same place.

Letters Patent No 480 Dated Aug 3. 1852.

The schedule referred to in these Letters Patent and making part of the same.

To all whom it may concern:

Be it known that we Garrison Smith, Henry Brown & Julius Bolzer of the County of Philadelphia, State of Pennsylvania have invented or produced a new design for cooking stoves and we do hereby declare that the following is a full & exact description of the same reference being had to the accompanying drawings making part of this specification, in which

Fig 1 is a side elevation of said cooking stove

Fig 2 is a front elevation of the same

a is the moulding of the hearth plate

b is the moulding of the doors.

These mouldings are entirely new having been formed by moulding planes made expressly for this stove.

d, d, d, d, d are raised panels on the doors each panel being bordered with the mouldings b.

The ornaments are formed by combinations of rosettes (c) rods (f) petals (i) and

2

Des. 480

French scrolls (4) arranged upon the several doors as represented in the drawings. The ornament on the side plate above the oven door, is formed of the rosette, rods, and petals without the scrolls. The foot is adorned with a combination of leaf and scroll work as represented at 5

What we claim as our invention and desire to secure by letters patent is the design and configuration of the mouldings, conical rods of petals to rosette & scroll & foot & as herein described forming an ornamental design for a cooking stove.
